HOLDER FOR PAPER CUP OR THE LIKE

Edwin S. Sinaiko, 5555 S. Everett Ave., Chicago, Ill.

Filed Sept. 20, 1961, Ser. No. 66,800

Term of patent 14 years

(Cl. D44—10)

FIG. 1 is a side elevational view of a holder for paper cup or the like embodying my new design;

FIG. 2 is a perspective view thereof;

FIG. 3 is a top plan view thereof; and

FIG. 4 is a bottom view thereof.

I claim:

The ornamental design for a holder for paper cup or the like, substantially as shown.
